MOSES MOSLER, OF CINCINNATI, AND CARL BARTELS, OF HAMILTON, OHIO, ASSIGNEES
TO THE MOSLER SAFE COMPANY, OF NEW YORK, N. Y.

SAFE.

1,186,597.

Specification of Letters Patent. Patented June 13, 1916.

Application filed December 13, 1915. Serial No. 66,501.

To all whom it may concern:

Be it known that we, MOSES MOSLER, a citizen of the United States, residing at Cincinnati, Hamilton county, Ohio, and CARL BARTELS, a citizen of the United States, residing at Hamilton, Butler county, Ohio, have invented certain new and useful Improvements in Safes, of which the following is a specification.

Our invention will be readily understood from the following description taken in connection with the accompanying drawing in which:—

Figure 1 is a front elevation of a compound safe exemplifying our invention, the door of the outer safe being illustrated in the open position, and wall-portions of both safes being illustrated in vertical section in the plane of line *a* of Fig. 2; Fig. 2 a horizontal section of the outer safe and a plan of the inner safe, portions of the walls and doors of both safes appearing in horizontal section in the plane of line *b* of Fig. 1; and Fig. 3 a horizontal section, in the plane of line *b* of Fig. 1, of the wall of one of the safes, at the joint of separation between its sections, the joint being shown as open.

In the drawing:—1, indicates the outer component of a composite safe which will be herein termed the outer safe; 2, its door; 3, the rear portion of the outer safe; 4, the front portion of the outer safe; 5, a joint of separation between the front and rear portions of the outer safe; 6, a cover-band covering the outer portion of the joint between the two sections of the outer safe, this band being preferably secured permanently to one of the sections, as by means of rivets; 7, screws serving to secure the cover-band to the second section of the outer safe; 8, a cover-strip over the inner portion of the joint between the two sections of the outer safe, this strip, whether complete around the inside of the outer safe or formed in sectional strips, being preferably secured permanently to one section of the outer safe, as by means of rivets; 9, screws serving to secure the cover-strip 8 to the opposite section of the outer safe; 10, a safe, hereinafter termed the inner safe, disposed within the outer safe and having the outer surface of its walls disposed inwardly at a distance from the inner surfaces of the walls of the outer safe; 11, spacing

members, as blocks or strips, disposed in the spaces between the inner surfaces of the outer safe and the outer surfaces of the inner safe and serving to maintain the two safes in fixed relationship to each other; 12, the door of the inner safe; 13, a margin-plate secured against the front of the inner safe and extending out to the wall of the outer safe; and 14, fireproof filling which may form a part of the wall and door of the outer safe and a part of the wall and door of the inner safe and may fill the spaces between the two walls of the two safes, except at the doors.

Both the inner and outer safes are illustrated as being provided each with a door at its front, which is all that is needed if the safe is to be opened from one of its faces only, and the illustration shows the door of each safe as being of single type, that is to say, each door is supported on hinges at one side of the door-jamb and is formed of one member, as distinguished from double doors, each covering but half of its door-opening and supported by hinges at each side of the door-opening. Our invention is indifferent as to these variations in construction.

The walls and doors of either or both safes may follow usual constructions of safes, that is to say, either of the safes may involve a plurality of plates with fireproof filling between the plates, or the walls of either safe may be formed in any other usual manner. The space between the walls of the outer safe and the inner safe forms an air space having within itself heat insulating qualities, so that fireproof filling within this space is not essential.

Looking at the outer safe it is to be observed that it is, within itself, a self-contained safe, and looking at the inner safe it is to be observed that, within itself, it is a self-contained safe. Either of these two safes may be used separately precisely as though they had not been constructed with any view to their association with each other in order to form a composite safe. But in the present instance, the exterior of the inner safe is so much less than the interior of the outer safe that the outer safe may contain the inner safe and leave an air space or a filled space between the two safes. In the illustration, the door-opening in the outer safe is shown large enough to admit

the inner safe, but, in case the door-opening of the outer safe is too small to permit the insertion of the inner safe, the inner safe may obviously be inserted in the outer safe 5 before the two sections of the outer safe are secured to each other. The formation of the outer safe in united sections permits of the outer safe being gotten into an apartment through a doorway too narrow to permit 10 the passage of the outer safe in its complete form, and the same construction may be applied to the inner safe if the narrowness of doorways into the compartments indicates its necessity.

15 When the inner safe has been disposed within the outer safe then the margin-plate may be applied and secured by any adequate means, as by means of screws securing the margin-plate to the front of the inner safe, 20 the margin-plate masking the space between the inner and outer safes. When the safes are employed in conjunction, to form a composite safe, there is nothing in the frontal appearance of the safe, when open, to indicate 25 that the safe is not an integral safe instead of a composite safe.

In the safe-making art the distinction between the expression "safe" and "vault" is a rather shadowy one and seems to be dependent largely upon size of structure.

30 We wish it to be distinctly understood that while we have termed our invention an improvement in "safes" the term is to be

considered as comprehending structures so small that they might not be popularly termed vaults, or so large that they would not be popularly termed "safes." As a broader definition we would say that our improvement in safes comprehends an improvement in safes or vaults.

40 We claim:—

A composite safe comprising, a self-contained outer safe provided with a door-jamb in one of its walls, a door hinged to such outer safe and closing into said door-jamb, 45 an inner safe complete within itself and removably disposed within the outer safe and unsecured thereto and having exterior dimensions less than the interior dimensions of the outer safe so as to leave a space between the walls of the two safes, spacing members disposed in such space and serving to position the inner safe within the outer safe, and a margin-plate secured to the front of the inner safe and having its outer 50 edges at the walls of the outer safe and serving to close the front of the space between the inner and outer safes and hide that space when the door of the outer safe is open, combined substantially as set forth. 55 60
